UNITED STATES PATENT OFFICE.

PATRICK M. WILLIAMS, OF NORTH WILKESBORO, NORTH CAROLINA, ASSIGNOR TO
MOORE DRY KILN COMPANY, OF JACKSONVILLE, FLORIDA, A CORPORATION OF
FLORIDA.

PIPE SYSTEM FOR KILNS.

Application filed October 15, 1923. Serial No. 668,776.

To all whom it may concern:

Be it known that I, PATRICK M. WILLIAMS, a citizen of the United States, residing at North Wilkesboro, in the county of 5 Wilkes and State of North Carolina, have invented certain new and useful Improvements in Pipe Systems for Kilns, of which the following is a specification.

This invention relates to an improvement 10 in dry kilns for curing lumber, and more particularly to a pipe system for kilns.

The present invention is designed for 15 drying wood of low moisture content, such as wood for furniture stock such as oak and gum, and it consists in a pipe system adapted to receive its supply from a low steam pressure or exhaust steam, in which case it is found practical to arrange a greater number of pipes at the dry end and 20 feed the low pressure steam to the first feed header at the dry end, the steam when traveling through the first few feet of pipe giving off more heat than when the steam has traveled a little distance. Again, owing 25 to the fall of the kiln from the green end or receiving end to the dry end or discharge end, it is found that by feeding the steam in at the dry end a more even temperature schedule can be maintained 30 throughout the kiln.

In the accompanying drawings:—

Fig. 1 is a longitudinal sectional view 35 through the kiln;

Fig. 2 is a transverse vertical section taken on line 2—2 of Fig. 1;

The numeral 1 represents a kiln of suitable construction and dimensions, and the end 2 at the left is the inlet or green end of the kiln, it having the usual arrangement 40 of track rails 3 extending therethrough on a gradual fall from the green or loading end to the dry or unloading end 4.

In the construction shown in Fig. 1, the piping 5 extends from the top-header 6 located at the dry end to a point adjacent the green or loading end, and from that point the piping extends back to a point beneath the top header 6, at the dry end, and then back again to a bottom header 7 some distance in from the dry end, and at the bottom 50 of the chamber containing the heating pipes. A feed pipe 6' is connected to the header 6 at the dry end. In that exhaust steam is used in the heating plant, the headers 6 and 7 are made extra large.

At the green or loading end in this kiln there is no piping whatever and no ventilation. It is desired to make the green end of the kiln a kind of a sweat-box or dead-air space, for softening the fibre of the 60 lumber and opening the pores.

Thus it is the intention to subject the stock when it enters the kiln to a moist air and low temperature and let it move progressively toward the hot and dry end of 65 the kiln, the arrangement of the pipes as described giving this result.

A steam spray pipe 8 is arranged centrally of the kiln and beneath the rails 3 at the green end, preferably in the space 70 that is free from the main heating pipes. Additional spray pipes 9—9 are arranged along the walls of the kiln approximately centrally of the heated compartment at the green end, these pipes leading laterally from 75 the spray-pipe 8.

Ventilators 10 are located at intervals in the roof as shown in Fig. 1.

Thus it will be seen that upon entering the kiln the stock is subjected to a moist 80 air and low temperature, and the lumber being mounted on trucks mounted on rails 3 is moved gradually toward the hot or dry end of the kiln. Most of the pipes being at the unloading or dry end, the heat waves 85 move to the coldest end and in this way the heat waves move up next to the roof, back down to the green end of the kiln, and down under the heating coils.

This pipe system is especially adapted to 90 exhaust steam. I make the top header which is located at the dry end equivalent in size to the exhaust pipe of an engine and in this way get maximum heat at the dry end, regardless of pressure, and this pipe 95 system maintains throughout the entire kiln its proper balance of heat and humidity. In fact, I have found that this pipe system responds so beautifully in every case I have so far tried it that I use it in other installations where space below the track will permit of it. I prefer it because entering steam in a progressive dry kiln at the dry end has many decided advantages.

I claim:

1. A dry kiln having a heating system therein and sprays discharging a mist therein at least two horizontal levels.

2. A dry kiln having a heating system therein and sprays discharging a mist there-

- 2
- in along to horizontal levels, both sprays being located only at the green end of the kiln.
3. A dry kiln having a graduated heating system therein and humidity sprays discharging a vapor therein along at least two horizontal levels.
4. A dry kiln having a heating system therein, a moist steam spray system located within the kiln in the region of the bottom 10 of the material being treated, and a second moist steam spray system located in a higher horizontal plane within the kiln.
5. A dry kiln having a heating system therein, a misty vapor spray system located 15 within the kiln below the material being treated, and a second misty vapor spray system located above said first-mentioned spray system.
6. A dry kiln having a heating system in 20 the lower portion thereof, a moist steam spray system discharging into the kiln from below the material being treated, and a second moist steam spray system located above said first mentioned spray system.
7. A dry kiln having a graduated heating system extending from one end thereof to 25 a point near the opposite end providing a substantially unheated area at the last-mentioned end, a humidity spray system located below the material being treated, and a second humidity spray system located within the kiln above the bottom of the material.
8. A dry kiln having a heating system 30 therein, a moist steam spray located within the kiln below the material being treated, and secondary moist steam sprays located within the kiln at a higher elevation than the first mentioned spray.
9. A dry kiln having green and dry ends 35 for receiving material to be treated, a graduated heating system extending from the dry end to a point near the green end providing a substantially unheated area at the green end, a steam spray located below the material being treated, and steam sprays located 40 at a higher elevation than the first-men-
- tioned steam spray and within the unheated 50 area.
10. A dry kiln having green and dry ends, a heating system of progressively increasing intensity toward the dry end, and moist spray pipes located adjacent the side walls and bottom of the kiln at the green end thereof.
11. A dry kiln for receiving material to be 55 treated and having a heating system therein, a moist steam spray located in the bottom of the kiln below the material being treated, and moist steam sprays located in the upper portion of the kiln for simultaneously spraying the material, at upper and lower regions.
12. A dry kiln having a drying chamber for receiving material to be treated, a heating system within the kiln, a live moist steam spray system located in the lower portion 60 of the kiln, and moist steam sprays located in the upper portion of the drying chamber for uniformly spraying the material being treated.
13. The combination in a dry kiln having 70 a green end and a dry end, of a pipe system extending from the dry end to a point near the green end, thence back to the dry end, and a spray system located at the green end unoccupied by the heating system, and a supply pipe connected at the dry end of the pipe system.
14. A dry kiln having a green end and a dry end, a top header adjacent the dry end, a bottom header partway between the dry 80 and green ends, piping extending from the top header to a point near the green end and back to a point adjacent the dry end, thence to the bottom header, a supply pipe leading to and connected with the top header of the dry end, and spray pipes located along the side walls and bottom of the kiln at the green end thereof.
- In testimony whereof I affix my signature.

PATRICK M. WILLIAMS.
